IRONING MACHINE

John W. Racklyeft, Cleveland, Ohio, assignor to
The Apex Electrical Manufacturing Company,
Cleveland, Ohio, a corporation of Ohio

Application January 16, 1937, Serial No. 120,959

15 Claims. (Cl. 38—59)

This invention relates to ironing machines and it constitutes a continuation-in-part of my co-pending applications Serial No. 621,658 which was filed July 9, 1932, and issued as Patent No. 2,071,264, on February 16, 1937, and Serial No. 111,695 which was filed November 19, 1936.

The present invention has for its objects the provision of an ironing machine having an inexpensive and compact operating mechanism; the provision of an ironing machine having a power-operated roll with a disconnectible driving connection inside the roll and means outside the roll for controlling such connection; the provision of a power-operated ironing machine having a minimum number of clutches; and the provision of an ironer roll drive as described, in combination with an ironer of the type in which either the roll or the shoe is the shiftable member and in which the ironer roll drive is automatically connected to drive the roll when the roll and shoe are shifted to an operative pressing position and automatically disconnected when the roll and shoe are separated one from the other.

These and other objects of the invention will become more apparent and better understood after consideration has been given to the following detailed description of the invention taken in connection with the drawings which show, merely by way of illustration, structure adapted for carrying out the objects of the invention.

Stated in general terms, the invention relates to an ironing machine having a padded roll and a heated shoe and power means for effecting both the rotation of the roll and the shifting of one or the other of such members into and out of pressing contact with the other. The machine also includes a suitable gear case which serves as a pedestal for supporting the roll solely at one end. The power means includes suitable gearing inside the gear case and associated gearing inside the roll. Manually operable control members are conveniently located on the exterior of the gear case and suitable control mechanism inside the gear case is operatively associated with such control members. The mechanism inside the roll includes a disconnectible driving connection for effecting the rotation of the roll in a controllable manner in accordance with the operation of the mechanism in the gear case and the manually operable control members located exteriorly thereof.

In the drawings, Figure 1 is a side elevational view of an ironing machine, illustrating one form of the invention; Figure 2 is an enlarged end

5 view of the machine shown in Figure 1, with portions of the machine broken away and shown in section; Figure 3 is a sectional view taken on line 3—3, Figure 2; Figure 4 is a detail view of the roll driving gears shown in Figure 2 to illustrate the disengaged position of the driving gears when the roll is not being driven; Figure 5 is an enlarged detail central sectional view of some of the structure by means of which the rotation of the roll may be prevented during the operation of the machine so that it may be used as a presser; Figure 6 is a side elevational view, partly in section, of an ironing machine, illustrating a modification of the invention; Figure 7 is an enlarged plan view, partly in section, showing the mechanism inside the roll for effecting the rotation and the shifting of the roll; Figure 8 is a sectional view taken on line 8—8, Figure 7; Figure 9 is a perspective view of an ironing machine, illustrating yet another modification of the invention; Figure 10 is an enlarged detail view of the operating mechanism of the machine shown in Figure 9; Figure 11 is an enlarged side elevational view, partly in section, of the machine when viewed from a point opposite to the right hand end thereof, the cover of the gear case at this end of the machine being removed to show the operating parts inside the gear case; Figure 12 is a plan view, partly in section, of the roll driving and shifting mechanism which is located inside the roll; Figure 13 is a central detail sectional view of the roll carrier and its drive shaft; Figure 14 is a detail perspective view of the controller for the roll driving clutch; Figure 15 is an enlarged detail view of the cam and clutch which effect the shifting movements of the roll; Figures 16 and 17 are detail sectional views taken on line 16—16, Figure 15, illustrating the cooperating elements of the clutch when in their engaged and disengaged positions respectively; Figure 18 is a central sectional view of the clutch; and Figure 19 is an end elevational view of the clutch, illustrating in full and dotted lines the inoperative and clutch-operating positions respectively of the clutch controller.

The form of the invention illustrated in Figures 1 to 5, comprises the base or table top 1 mounted upon supporting legs 2 and carrying a gear case 3 from which an ironer roll 4 projects. On the top of the base 1, there is located a bracket 5 for the supporting arm 6 of an ironer shoe 7. The bracket 5 provides a mounting for one end of a tube 8 which extends between the gear case 3 and the bracket 5.

In the present form of the invention, the shoe

7 is adapted to be moved into and out of pressing contact with the roll. Suitable power-operated mechanism, as will be described in detail presently, is housed within the gear case 3 for effecting in a controllable manner the shifting of the shoe and the rotation of the roll.

The gear case 3 is provided at one side with a hollow boss 10 for receiving one end of the tube 8. The operating mechanism of the machine is driven by a motor 11 having a pulley 12 for a driving belt 13 which connects the motor to a pulley 14 of the ironer mechanism. The pulley 14 is fixedly connected to a shaft 15 having a worm 15a in mesh at all times with a worm gear 16.

The worm gear 16 is provided with axially extending hub or sleeve portions 16a, which cooperate with coiled clutch springs 17 and 18. The clutch spring 17 is fixed at one end to a shaft 20 which is journaled in the bearing sleeve 20a carried by the gear case boss 20b. The clutch spring 17 is provided with a free end which is adapted to be engaged by a stop which is operatively connected to the manual control member 17a so that when the stop is in contact with the end of the spring, the clutch is prevented from wrapping around the sleeve 16a to the right of the gear 16. Upon release of the free end of the clutch spring 17, it will wrap around such sleeve part and connect the worm 16 in driving relation with respect to the shaft 20.

One end of the clutch spring 18, which is located to the left of the worm gear 16, is fixed with respect to an eccentric 21 which is also journaled on the sleeve 20a. The eccentric 21 is received in one end of a connecting rod 22 and at its other end the rod 22 is connected by means of a pin 23 to a crank arm 24. The other end of this crank arm is fixedly attached to one end of a torsion rod 25 and the opposite end of the torsion rod is fixedly connected to the shoe-supporting arm 6 which is pivotally connected at 26 to the rear part of the shoe 7.

The clutch spring 18 is provided with a free end adjacent to the worm gear 16. A manually operable control member 18a is provided for the purpose of moving a pair of associated stops positioned 180 degrees from each other, into and out of the path of the free end of the clutch spring 18, so that when the control member 18a is momentarily depressed, the clutch spring 18 will wrap around the sleeve part 16a and rotate the eccentric 21 through substantially 180 degrees, where the clutch spring is engaged by the stop opposite to the one which was just moved out of engagement with the free end of the clutch spring. The next time the control member 18 is depressed, the eccentric 21 will be moved another half turn and in this manner the eccentric may be operated in steps of 180 degrees. The stops which are associated with the controls 17a and 18a correspond substantially to the stops 17c and 18c which are shown in Figure 7.

In view of the foregoing, it is apparent that when the eccentric 21 is rotated, it will serve to shift the shoe into and out of pressing contact with the roll. The roll is carried by a pair of bearing members 27 and 28, journaled for movement on a roll supporting tube 30 which is rigid with the gear case 3. An internal gear 31 is secured to the roll internally thereof alongside of the bearing member 28. The shaft 20 projects outwardly from the gear case 3 and into the roll where it is fitted with a pinion 32.

The shaft 20 provides a mounting for a brack-

et 33 which is rotatably journaled on this shaft. The bracket is provided with a bearing pin 34 which forms a bearing for a second pinion 35 which meshes at all times with the pinion 32.

5 The pinion 35 is adapted for meshing engagement with the internal gear 31 secured to the roll internally thereof. A spring 37 is provided to urge the bracket 33 and the pinion 35 in a direction toward the adjacent portion of the internal gear 31. Beneath the shaft 20, the bracket 33 is provided with an angular extension 38 by means of which the pinion 35 is mechanically shifted into and out of meshing engagement with the internal gear 31.

15 The mechanism for accomplishing the shifting of the pinion 35 comprises a connecting link 40 which is pivotally connected at one end to the pin 23 and at its other end it is pivotally connected at 41 to a crank member 42 which is fixed to one end of a tubular shaft 43. The other end of the tubular shaft 43 is provided with a cam 44 which is adapted to be moved into and out of meshing engagement with the extension 38 of the pinion bracket. The tubular shaft 43 is journaled in a suitable bearing member 45 which may be formed integrally with the gear case 3.

20 In view of the foregoing, it is apparent that when the roll-shifting mechanism is operated to move the shoe into contact with the roll, the connecting rod 40 will be moved downwardly to the position shown in Figure 2, lifting the cam 44 out of contact with the extension 38 of the pinion bracket, thus permitting the pinion 35 to move under influence of the spring 37 into mesh with the internal roll gear 31.

25 The reaction between the pinion 35 and the roll gear 31 tends to maintain these gears in meshing engagement with each other. When the shoe is shifted away from the roll, the lever 40 moves upwardly and rotates the cam 44 into engagement with the bracket extension 38, and in this manner, the pinion 35 is shifted out of meshing engagement with the internal gear 31 of the roll. Additional mechanism to permit the machine to be used for pressing operations is provided for preventing at times the rotation of the roll when the shoe is moved into pressing contact therewith.

30 This mechanism comprises a manually operable control 46 located outside the gear case 3 and fixed to a shaft 47 which is pivotally mounted inside the gear case. The shaft 47 is provided with a bracket 48 which is pivotally connected at 50 to a link 51 which in turn is pivotally connected at 52 to a crank 53 which is fixed with respect to one end of a shaft 54. The shaft 54 is journaled inside the tubular shaft 43 and at its opposite end it is provided with a cam 55 located alongside the cam 44.

35 The cam 55 is pinned at 56 to the shaft 54 and when the manual control 46 is moved downwardly, a corresponding movement of the cam 55 takes place and the cam is thus shifted into engagement with the extension 38 of the pinion supporting bracket, and in this manner, the pinion 35 may be prevented from meshing with the internal gear 31 under influence of the spring 37. When the manual control member 46 is moved to the position shown in Figure 2, the cam 55 is moved away from the extension 48 of the pinion bracket and the shifting of the pinion is controlled entirely by the cam 44 and the elements which are associated with this cam and with the shoe-shifting mechanism. The

control 46 and the parts associated with it are fitted so that there is sufficient friction to maintain the control 46 in its adjusted positions.

In the form of the invention illustrated in Figures 1 to 5, the worm gear 16 is driven in a counter-clockwise direction, as viewed from the right hand end of the machine, so as to rotate the roll 4 in an opposite or clockwise direction. The clutch springs 17 and 18 are wound in opposite directions, as is shown in Figure 3, so that when the free end of each of these springs is released, their inherent tension will cause them to engage and wrap around the sleeve parts 16a.

During the operation of the machine, the manually operable control member 46 is ordinarily used to prevent rotation of the roll when the machine is used for pressing operations. The control 17a and the clutch formed in part by the clutch spring 17 which is associated with this control, provide a convenient and easily operable auxiliary means for temporarily stopping the rotation of the roll when it is used as an ironer or a mangle, as may be desirable at times when heavy or very wet articles are being ironed.

In the form of the invention illustrated in Figures 6 to 8, there is provided a base 1 having legs 2, a gear case 3a, a roll 4, a bracket 5, a shoe-supporting arm 6, a shoe 7 and a tube 8, similar to the corresponding elements first described, and somewhat similar operating mechanism under control of the manually operated members 17a and 18a is located within the gear case 3a.

The present construction differs from the construction earlier described in that the roll 4 is the shiftable member and in that the roll is supported from a point intermediate its ends by means of a pair of bearing members 57 and 58 which are rotatably carried on a shaft 60. The shaft 60 is fixed to the upper end of a crank arm 61 which is in turn fixed to an oscillatable shaft 62. This shaft corresponds to the shaft 25 and it serves to shift the roll 4 into and out of pressing contact with the shoe 7. The roll-supporting tube 63 is also somewhat shorter in length than the tubes 30 previously described and it is carried from a boss 64 which is located below the axis of the roll when the roll and shoe are in pressing contact.

The oscillatable shaft 62 is located inside the tube 63 and the outer end of this tube provides a bearing for supporting the outer end of the shaft 62. In this form of construction, the roll driving pinion 65 is carried by a U-shaped bracket 66 which is rotatably journaled upon the tube 63. The bracket 66 is slotted at 67 for receiving a pin 68 which is fixed to the tube 63. The slot and the pin are provided for the purpose of limiting the movement of the U-shaped bracket 66.

In view of the foregoing, it is apparent that when the roll 4 is moved into contact with the shoe, the internal gear 70 inside the roll will move into meshing engagement with the pinion 65 which is connected to the shaft 72 by means of the couplings 73 and 74 and the shaft 75. In the event that the teeth of the gear and pinion do not line up properly, the pinion is free to move with the gear until the gear teeth do line up, whereupon the force of reaction between the gears insures the maintaining of proper meshing engagement between the pinion 65 and the internal gear 70. When the roll is shifted away from the shoe, the stop which is provided by the pin 68 and the slot 67 of the U-shaped bracket 66

serves to hold the pinion 65 out of meshing engagement with the internal gear 70.

The gearing for controlling the shifting and rotational movements of the roll, as is best shown in Figures 6 and 7, comprises a motor 11, an associated pulley 12 and a belt 13 to connect the same to a pulley 14. The pulley 14 is fixed to rotate with a shaft 15 carrying a worm 15a which is adapted to mesh with a worm gear 16. The worm gear 16 is provided with axially extending hub or sleeve parts 16a and it is adapted to freely rotate upon a bearing sleeve similar to the sleeve previously described, in connection with the form of the invention illustrated in Figures 1 to 5.

Several turns at the free end of each of the clutch springs 17b and 18b each overlie one of the sleeve parts 16a. A stop member 17c for the free end of the clutch spring 17b is operatively associated with the control member 17a and a pair of stops 18c located substantially 180 degrees from each other, are associated with the manually operable control member 18a for controlling the clutch which is formed by the spring 18b, so that such clutch may be operated to rotate an eccentric member 76 in steps of 180 degrees. The eccentric 76 is operably connected by means of the link 77 to a crank 78 fixed to the rocker shaft or oscillatable shaft 62.

The manually operable control 17a is used to prevent rotation of the roll when the machine is used for pressing operations and it may also be used for momentarily stopping rotation of the roll during ironing operations. Normally, however, the clutch spring 17b is in operative engagement with the sleeve part 16a so as to drive the shaft 72 ordinarily at all times while the machine is being used.

In the form of the invention illustrated in Figures 6 to 8, the worm gear 16 rotates in a clockwise direction, as viewed from the right hand end of the machine, so as to rotate the roll in the same direction. The clutch springs 17b and 18b are wound in opposite directions, as shown in Figure 7, so that when they are released to engage the sleeve parts of the worm gear 16 they will wind around and tightly engage the same for the purpose of driving the shaft 72 in the case of the clutch spring 17b and to rotate the eccentric 76 in the case of the clutch spring 18b.

In the two different forms of ironing machine mechanisms which have been described herein, it is intended that the internal gear in the roll and its driving pinion mesh with each other at least partially, before the roll and shoe contact each other so that no substantial load is imposed on the gears at the instant of their engagement or disengagement. Because of this, the roll driving connection is effected in a quiet manner and the specified arrangement has the further advantage of reducing wear on the ends of the gear teeth and thus preventing such portions of the gear teeth from quickly becoming worn or broken.

In the form of the invention illustrated in Figures 9 to 19 80 indicates the housing of the driving instrumentalities comprising an upper compartment 81 and a lower compartment 82. Mounted within the lower compartment 82 is an electric motor 83 receiving current from a source of electric energy. Said motor is mounted within the said housing in a convenient manner as by means of screws 84, received in suitably threaded holes formed in the outer wall 3 of the casing 80. Mounted on the shaft 86 of the motor 83 is a pulley 87.

A shaft 88 is positioned in the upper compartment 81 and carries a pulley 90 on one end. The shaft 88 extends through the front wall 91 of the housing 80 and leads into another compartment 92 in front of the housing 80. Said compartment 92 is formed in part by a cover plate 89 which is hinged to the housing 81 as shown at 93, and is firmly held in closed position by means of a screw 94 fastening the same to the housing 80. Removal of the screw 94 will allow opening of the compartment 92 to give easy access to the instrumentalities mounted therein. A belt 95 connects pulley 87 and pulley 90 for power transmission.

As stated before, the shaft 88 is mounted within the upper compartment 81. This is clearly illustrated in Figures 10 and 11. The outer wall 91 of the casing 80 comprises a reinforced portion 96 having a flanged bore 97. An upwardly extending portion 98 is carried by the wall portion 100, which separates compartments 81 and 92 and it has a bore 101 for the reception of a ball bearing mounted on one end of the shaft 88. A ball bearing is mounted on the other end of the shaft 88 and is arranged to fit properly in the bore 97. A retaining member 102 is employed to hold the bearing members properly in place and to prevent motion of the shaft 88 in a longitudinal direction. Said retaining member 102 is secured to the reinforced portion 96 of the wall 91 by means of screws 103. Intermediate the bearings of the shaft 88 is a worm 104 mounted on the shaft 88 in any suitable manner.

The reinforced portion 96 of the casing 80 is connected with the upwardly extending portion 98 by means of a bridge 105 having a bearing portion as shown at 106 in Figure 11. A shaft 107 is mounted within said bearing 106 and extends into a bearing mounted in a centrally bored boss 108 of the housing 80.

The free end of the shaft 107 extends outwardly from the bearing 106 and carries a worm gear 111 keyed thereto and held properly in place by means of a locking member 112. Said worm gear 111 is in suitable engagement with the worm 104 to transmit rotation from the worm to the shaft 107. A gear 113 and a ball clutch 114 are mounted between the bearing 106 and the boss 108 and a coil spring 115 is placed therebetween for purposes to be hereinafter set forth.

The ball clutch 114, details of which are shown in Figures 15, 16, 17, 18 and 19, comprises an eccentric cam 116 having rigidly connected therewith a ring like intermediate clutch portion 117 provided with a bore 118 for the reception of a clutch ball 120. An inner clutch member 121 of sleeve-like formation, having cavities 122 for the reception of the clutch ball 120, is mounted within the member 117 and is secured to the square portion 124 of the shaft 107, as clearly shown in Figure 16. An outer clutch member 125 of ring-like configuration, having a longitudinal groove 126, is adapted to cause in different positions of the ring 125 with respect to the member 117, engagement or disengagement of the clutch.

An annular shoulder 127 is provided on the member 125 for the reception of a circular plate 128 having arms 130 and 131 extending through slots 132 and 133 formed in the shouldered end of the outer clutch member 125. The helical spring 115 is mounted on the shaft 107 between the spur gear 113 and clutch 114. Said spring grips the shaft under slight tension so that rotation of the shaft will tend to cause a corresponding rotation of the spring. One end of the

spring is free and its other end secured to the plate 128 by insertion of the same into a hole 115a in said plate 128. The spring 115 will tend to urge the plate 128 and outer clutch member 125 to the dotted line position of Figure 19 and the position shown in Figure 16, thus causing the engagement of the clutch members for transmission of rotation from the shafts 88 and 107 to the intermediate clutch member 117 and cam 116.

If the ball clutch 114 is in the disengaged position shown in Figure 17 and the full line position of Figure 19, the clutch ball will oscillate in a radical direction as there is nothing to restrain its motion, but if the clutch is engaged, as shown in Figure 16, the ball will not be permitted to move out of its respective cavity 122 as the surface of the ring 125 bearing against said ball will not permit such oscillatory movement of the same. The clutch actuating arms 130 and 131 and the spring 115 are for the purpose of controlling engagement and disengagement of the clutch and the operation of the same will be later described.

The housing 80 is provided with several sockets or bearings 134, 135, 136, 137 and 138. A standard or tubular member 140 tightly fits within the sockets 134 and 135. Another tubular member 141 is rotatably mounted within the standard 140 for purposes which will hereinafter become apparent. Two standards 143 and 142 are mounted within the sockets 136 and 137 and are secured therein against rotation by means of pins 144 and 143a. The free ends of the standards 143 and 142 opposite their sockets 136 and 137 carry a supporting member 145 and are secured thereto by means of pins 146 and 146a. A tubular shaft 147 is journaled within the socket 138 and extends through the lower portion 148 of the supporting member 145. The free end of said shaft, designated at 150, carries a supporting member or crank arm 151.

A roll supporting cage 152 is secured to a shaft 158 by means of a threaded portion 154 screwed on the threaded end 155 of the shaft 158. The shaft 158 and a shaft 153 rotate in a bushing 157 received within the upper portion of the supporting member or crank arm 151. At the point where the shaft 153 enters the bushing 157, there is a flexible joint connection between the shafts 153 and 158. This flexible joint connection is illustrated in Figure 13 and consists of a pin 160 mounted on the end of the shaft 153 and a sleeve 161 secured by means of a pin 162 to the shaft portion 158. Said sleeve has a slot 163 for the reception of the pin 160 so that when said pin is inserted in the slot of the sleeve member, a flexible driving connection will be obtained.

The other end of the shaft portion 153 is connected in a similar manner to a jaw clutch member 164 by a pin 165 which is rather loosely received in the slot 166 in said clutch member 164. A compression coil spring 167 of substantially the same diameter of shaft 153 is slid upon this end of said shaft with the end of the spring remote from the clutch in tight engagement with the shaft. A cotter pin 168 is inserted through a hole in shaft 153 to hold said spring in the desired engagement with the clutch member 164. One end of said spring is mounted within a hole 171 in said jaw member 164.

The result accomplished by this peculiar connection may be briefly described as follows:

If the jaw clutch formed by the clutch members 164 and 172 is disengaged and the yoke 173 is released so as to permit engagement of the

clutch members it will be obvious that at the same time if the jaw teeth 174 and 175 engage, there will be a large amount of friction between them at the surfaces of their teeth, thus preventing proper engagement of the same and causing unnecessary wear on such surfaces. Therefore, this novel construction permits the clutch member 164 to be rotated against the slight tension of the spring 167 until the pin 165 engages the side surface of the slot 166. The small amount of play provided by the slot 166 and controlled by the slight tension of the said spring will give both the jaw clutch members 164 and 172 sufficient time to engage properly before application of the load and any destructive friction on the driving surfaces of the teeth of said jaw clutch members will be substantially eliminated.

As previously described, the tubular member 147 is mounted for rotation in the socket 138 and extends through the same into the compartment 81 and carries a yoke 178. The other end of said tube 147 is guided through the bearing portion 148 and rigidly carries on its free end as previously described, the crank member 151. A pin 180 is mounted on said tube to contact with a cam shaped lip 181 formed on the yoke member 173 and it is adapted to control engagement and disengagement of the jaw clutch member 164. A detail of this yoke is shown in Figure 14. Said yoke is mounted by means of a bracket 182 to the housing 80, as shown at 183 in Figure 10. Said bracket 182 carries the yoke 173 to which are secured two pins 184 adapted for the purpose of engaging with an annular slot 185 in the jaw clutch member 164.

The downwardly extending cam portion 181 of the yoke 173 which contacts with the tube 147 and pin 180 of said tube is for the purpose of engaging member 181 to shift the yoke and the member 164 in one direction, causing disengagement of the clutch. Coil spring 167, which was mentioned before in connection with the mounting of the shaft 153, serves also for the purpose of shifting the clutch member 164 to effect the engagement of the clutch when the pin 180 is not in contact with the yoke cam portion 181. The effect of this operation will be later set forth.

A cam 187 is mounted in close proximity to yoke member 173, as shown in Figure 14, and said cam may be operated by a lever 188 to hold the yoke 173 in such a position as to perform a disengagement of the jaw clutch. This manual control for said clutch is desirable when the operator wants to stop the motion of the ironing roller while the same is pressed against the shoe for pressing operations, and the very desirable feature of this arrangement will be brought out later in this description.

The tubular standard 140 is mounted, as previously mentioned, within the sockets 134 and 135 and a pin 190 passing through the socket 134 and tube 140 holds the tube stationary against rotation. Another tube 141 is rotatably mounted within said tube 140 and two slots in the tube 141, which are indicated at 192, allow a certain motion of said inner tube without interference by the pin 190. A pin 193 is secured to the inner tube 191, holding a sleeve 194 in proper fixed relation with said inner tube.

A slot 195 is provided in the outer tube member 140 to allow a certain amount of angular motion of pin 193 and sleeve 194. Said sleeve member 194 carries a cantilever tension spring 196 secured thereto by means of screws 197 and

198. The other end of said tension spring bears against the upper portion of the shoe arm 200. Said shoe arm 200 comprises two bearing members 201 and 202 surrounding tube 140 and being rotatable thereon. A spider 203 carrying the shoe 204 and secured thereto by means of screws 205, is hinged to said arm by a pin 206.

It will be obvious that if the inner tube 141 is locked in a certain position, a pressure will be created in the spring 196, tending to force the arm 200 and shoe 204 against the padded ironing roll 207, said ironing roll 207 being carried by the supporting member 152, as previously mentioned therein. The member 151 and the roll 207 may be swung toward or away from the shoe, as illustrated in full and dotted lines in Figure 11, and such motion is caused by the movement of the shaft 141 and its associated yoke 178.

The shoe 204 may be easily detached from its supporting arm by removing bolt 206 and it can be very easily cleaned by releasing the lever 208 whereupon the shoe can be moved away from the roll to permit it to be swung about the bolt 206 to present its ironing surface in accessible position.

The sleeve 194 has an extension 211 adapted to move within a slot 212 on the bearing member 202 of the shoe supporting arm. This will limit the motion of the arm 200 so that when the roll is moved away from the shoe, as shown in dotted lines in Figure 11, the spring 196 does not cause the shoe to follow the roll as would occur if such means were not provided and when the lever 208 is released, the shoe can be tilted back only a limited distance.

The jaw clutch member 172 is mounted on a shaft 213, journaled in a boss 214, which extends into the compartment 81 of the housing 80. A spur gear 215, in mesh with a spur gear 113 on the shaft 107 is secured to the free end of shaft 213 within the compartment 81 and serves for the purpose of transmitting power from the gear 113 to the clutch members 172 and 164 and thence to the shaft 153.

The ironing roll 207 is held in such a position with respect to the housing 80 that the end of the ironing roll toward said housing may be used for ironing purposes in the same manner as the opposite open or free end of said ironing roll.

Sharp edges on said housing are eliminated. The outer configuration of the same is such as not to interfere with the ironing operation of the machine and the portion of the housing below the roll has its rearmost wall located forwardly of a vertical plane through the lowermost line of contact between the ironer roll and shoe whereby ample space is provided for the passage of goods being ironed at the end of the roll adjacent to such housing.

It should be noted that the tensioning means for regulating the pressure between the shoe and the ironing roll is mounted on the supporting arm of said shoe and no tensioning means within the roller is necessary, thus simplifying very much the construction of the supporting means for the roll.

As previously stated, the tubular member 147 carries a yoke 178; the said yoke 178 contacts with the outer circumference of cam member 116 on the clutch 114 so that if the clutch is engaged, the cam member 116 normally will rotate one hundred and eighty degrees, causing a certain motion of the yoke 178 which is transferred to the tubular member 147 and pin 180 actuating

the jaw clutch and rotating member 151 as previously mentioned.

An emergency shoe release lever 208 is secured to the inner tube 141 and held by a locking means 216 in position so as to allow the contacting of the shoe with the ironing roll. The lock member 216 is provided with a trip lever 217 so that the locking means 216 may be swung out of the way of the free end of arm 208. This releases the shoe 204 from the roll for cleaning and safety purposes. To lock the shoe 204 again in its original position, it is only necessary to press the free end 218 of arm 208 downwardly until the locking member 216 which may be under the influence of a suitable spring, engages said portion 218. The ironing roll 207 is formed with an inwardly projecting longitudinal rib 220 adapted to engage with the slots 221 of the cage 152 to hold said roll against rotation on this supporting member and to allow transmission of power from the same to the roll.

The ball clutch actuating arms 130 and 131 which control the engagement of the ball clutch, abut against the extension 222 of an arm 223 mounted upon a shaft 224 having a trip lever 225 to cause disengagement of the clutch 114. Actuation of the trip lever 225 will swing the extension 222 on the arm 223 out of the path of the clutch actuating arms 130 and 131 and spring 115 will cause engagement of the said clutch. The arm 223 upon release of the lever 225 will then be returned to its normal position by the power of a coil spring 226 mounted with one end secured to the housing 80 while the other end is secured to the arm 223 as at 227. A removable cover 228 is provided permitting easy access to the compartment 81 and is secured thereto by means of screws 230.

It has to be noted that the shoe and roll are supported at their respective centers by means of their respective supporting devices. This will permit a certain amount of yielding of both the shoe and roll in a horizontal plane to compensate for different thickness of the material to be ironed. The centrally located roll bearing also prevents binding of the roll bearings due to bending of roll supports, as would occur if the roll bearings were in the ends of the roll and carried on a tube supported at one end only by the housing 80.

The operation of the machine shown in Figures 9 to 19 is as follows:

The cabinet is opened, electric current is supplied to the motor 83, and the same is started. Rotation of said motor is transmitted from pulley 87 to pulley 90 by means of the belt 95, causing rotation of shaft 88, worm 104, worm gear 111, spur gears 113 and 215, and clutch member 172. The clutch actuating arm 131 is in the position shown in Figure 11, abutting against the extension 222 of the arm 223, and the clutch 114 is now in a disengaged position, so that the shaft 107 will be permitted to freely rotate.

The yoke 178 contacting with the cam 116 of the ball clutch is in such a position as to cause disengagement of the jaw clutch 164 by means of pin 180 and yoke 173. The shoe 204 is provided with an electric heater 232 and this heater is connected by any suitable means with a source of electric current and has to become sufficiently hot before ironing operations can be started. The emergency shoe release lever 208 is in a position as shown in Figure 9, holding the shoe in proper relation to the ironing roll.

The material to be ironed is now placed upon

the ironing roll 207 and the trip lever 225 is operated. This will cause release of the clutch actuating arm 131 and the coil spring 115 of the ball clutch 114 will rotate the member 125 from the position shown in Figure 17 to the position shown in Figure 16 to cause engagement of said clutch, and rotational motion will now be transmitted from the clutch shaft 107 to the cam 116, shifting the yoke 178 which will cause such rotation of the tube 147 as will disengage pin 180 from the cam portion 181 of the yoke 173. The coil spring 167 will now force the clutch member 164 to the right to engage with the other clutch member 172, and the shafts 153 and 158 start to rotate, turning with them the roll supporting member 152 and the ironing roll 120.

At the same time, the rotation of the tubular member 147 will also cause a motion of the roll from the dotted line to the full line position of Figure 11, moving the roll 207 toward the ironing shoe 204 so that the material which has been placed upon said roll will be forced between the roll and the shoe, the latter pressing against the roll under a certain tension created by the spring 196 and the ironing operation may then be performed, as the material is fed through the machine. If the operator should, by accident, place his hand between the shoe and roller, the shoe may be immediately released by tripping the lever 217.

As previously mentioned, the clutch actuating arm 131 has been released and the clutch engaged by means of the spring 115. The releasing arm 223 moves back to its original position by means of the coil spring 226 and thereafter the clutch actuating arm 130 moves into position where it will abut against the extension 222, and the ball clutch will disengage automatically after one half of a revolution. During this time of engagement and disengagement of the clutch, the yoke 178 has been shifted sufficiently to cause the required rotation of member 151, necessary for moving the roll against the shoe and upon disengagement of the clutch, the ironing roll will be held in this position until the trip lever 225 is actuated again, causing clutch actuating arm 130 to be free to cause engagement of the clutch and to return the ironing roll to its original position away from the shoe.

After this action takes place, the clutch is again disengaged by the arm 131 engaging the lever 225. At the same time the pin 180 on the tube 147 will engage the portion 181 of the jaw clutch yoke 173 moving said yoke to the left, causing engagement between the clutch members 172 and 164. This will stop the rotation of the roll 207 and another piece of material to be ironed may be now placed upon said roll, or the operation of such ironing machine may be continued without releasing the roll from the shoe.

If it is desired to stop the rotation of the ironing roll while the same is in engagement with the shoe 204, it is only necessary to trip the lever 188. This will cause immediate disengagement of the jaw clutch member 164 so that the operator is in a position to apply more heat to a certain portion of the material to be ironed than the regular operation of the machine will allow, and the now non-rotatable roll can be shifted toward and from the shoe for pressing operation. It is, of course, understood that the roll is free to be turned by hand during the pressing operations at such times as when it is not in engagement with the shoe.

If the tension between the shoe and the ironing

roll needs readjustment, this can be accomplished by turning the screws 197 and 198. When the machine is out of operation, the electric current to the motor 83 and the current supply of the shoe 204 should be turned off and the cabinet may be closed.

The foregoing description and the accompanying drawings to which it relates, describes what might be termed the preferred modes of practicing the invention. It is to be clearly understood, however, that the invention includes each and every novel feature or combination of novel features herein disclosed, subject only to the restrictions of the prior art, and that the invention may assume other forms and it is to be limited to the particular and specific structure shown and described herein.

Having thus described my invention what I claim is:

1. A power driven ironing machine comprising the combination with a supporting structure, of an ironing roll mounted upon said structure for rotatable and lateral movements, means for effecting the lateral movement thereof and driving instrumentalities for the roll including a clutch device for controlling the lateral movement of the roll and for also controlling rotation of the roll, a second clutch for producing rotation of the roll, and mechanism inter-connecting the two clutches, whereby actuation of the first clutch actuates the second clutch, the said mechanism comprising a cam located on said first clutch, a yoke operated by the same cam, a shaft operated by the yoke, a pin mounted on the shaft, a second shaft for rotating the roll, one element of said second clutch being mounted upon the second shaft for producing actuation thereof, and a second yoke in engagement with the pin for actuating the second clutch to control rotation of said second shaft.

2. An ironing machine comprising in combination, an ironing roll, a gear case, a supporting member extending therefrom into the interior of the roll for carrying the roll, driving mechanism for the roll including a driving shaft, a driven shaft inside the roll, cooperating clutch members on the respective shafts for transmitting power from the driving shaft to the driven shaft, and actuating means inside said roll and exterior of the gear case for one of the clutch members for forcing said member into proper actuating engagement with the other clutch member.

3. In an ironing machine, the combination of an ironing roll mounted for rotation and also for lateral movement, an oscillatably mounted supporting member disposed interiorly of the roll at a point intermediate its length for carrying the roll, driving mechanism for the roll comprising a driving shaft and a driven shaft arranged inside the roll, said driven shaft being connected with said driving shaft for universal movement relatively thereto and having a universal connection with respect to the roll, whereby lateral movement of the roll is permitted without interrupting the driving connection between said driven shaft and said roll, and means for laterally shifting said roll supporting member.

4. A power driven ironing machine comprising the combination with a supporting structure, of an ironing roll mounted upon said structure and means adapting the roll for lateral movement thereof, driving instrumentalities for the roll including clutch devices one inside and the other outside said roll, the latter operating to control the lateral movement of said roll and also the

engagement and disengagement of the clutch device inside the roll which controls the rotation thereof, and manually operable means to prevent the engagement of said first named clutch device and to control the operation of the latter clutch device.

5. A power driven ironing machine comprising the combination with a supporting structure, of an ironing roll mounted upon said structure and means for supporting the roll for rotational and lateral movement, and driving instrumentalities for the roll including clutch devices one inside and the other outside said roll, the former operating to control the rotation of the roll and the latter operating to control the lateral movement of said roll, and an operating member for said last-named clutch device adapted to be actuated by said means for supporting the roll upon the lateral movement thereof whereby said clutch device outside the roll controls the engagement and disengagement of the clutch device inside the roll and thus controls the rotation thereof.

6. A power driven ironing machine comprising the combination with a supporting structure, of an ironing roll mounted upon the said structure, and means adapting the roll for lateral movement thereof, driving instrumentalities for the roll including interacting clutch devices which control the lateral movement of the roll and at the same time control the starting and the stopping of the rotation of the roll, a cam inside said roll and a manually operable actuating means therefor, and a yoke inside said roll on one of the clutch devices, said cam being adapted to engage said yoke to disable the interaction between said clutch devices whereby the roll may be laterally moved without being rotated.

7. A power driven ironing machine comprising the combination with a supporting structure, of a pair of cooperating ironing elements comprising a rotatable roll and a heated shoe, power means for rotating said roll, clutch means between said power means and said roll for controlling the rotation of the roll, means for supporting one of said ironing elements for bodily movement about an axis below the roll axis for shifting such element into and out of pressing engagement with the other ironing element, a rockable member operatively connected to said bodily movable ironing element, and a clutch control member inside said roll actuated by said rockable member whereby the clutch means are moved into and out of their engaged position when the ironing elements are moved into and out of pressing engagement with each other.

8. In an ironing machine the combination of an ironing roll, a shoe, a supporting member within the roll for carrying the roll, driving mechanism inside the roll for effecting its rotation including a driving member and a shiftable driving connection between said member and the roll for controlling rotation of the same, a gear case arranged at one end of said roll, power driven mechanism inside said gear case to effect relative movement between the shoe and roll, manual control means for said power driven mechanism and operative connections between the mechanism in said gear case and the driving mechanism in said roll, to effect a shifting of said driving connection coincident with the relative movement between the shoe and roll.

9. In a power driven ironing machine the combination with a supporting structure, of an ironing roll mounted upon said structure, a cooper-

ating ironing element, means enabling the roll to move laterally parallel to its axis toward and from the cooperating ironing element, and mechanism for rotating the roll and moving the same laterally parallel to its axis including dis- connectible driving connections, one inside and the other outside said roll, the latter operating to control the lateral movement of the roll and also the engagement and disengagement of the other driving connection.

10. A power driven ironing machine comprising the combination with a supporting structure, of pressing elements including an ironing roll and a shoe mounted upon such structure, means adapting one of said pressing elements for lateral movement with respect to the other of said pressing elements, and mechanism for effecting and controlling the rotation of the roll including disconnectible driving connections, one being inside the roll and controlling the rotation of the roll, and the other being outside the roll, the latter operating to control the engagement and disengagement of the driving connection inside the roll and also the lateral movement of said laterally movable ironing element.

11. A power driven ironing machine comprising a supporting structure, cooperating pressing elements mounted thereon, including a roll and a shoe and power driven means for effecting rotation of the roll and for shifting one of said pressing elements into and out of contact with the other, said power driven means including disconnectible driving connections, one being inside the roll and controlling the rotation of the roll and the other being outside the roll, the latter operating to control the engagement and disengagement of the driving connection inside the roll and also the lateral movement of said laterally movable pressing element.

12. A power driven ironing machine comprising the combination with a supporting structure, of pressing elements including an ironing roll and a shoe mounted upon said structure, one of said elements mounted to move laterally with respect to the other and mechanism for effecting and controlling rotation of the roll including disconnectible driving connections, one being inside the roll and controlling rotation of the roll, and the other being outside of the roll, the latter operating to control the engagement of the driving connection inside the roll and also the lateral movement of said laterally movable pressing element.

13. In an ironing machine, a gear casing at one end thereof, a roll and a cooperating shoe, a shaft projecting from said gear casing into said roll, a power unit, eccentric means carried by said shaft within said roll and operatively

connected thereto, a second shaft projecting from said casing, means including a flexible driving connection operatively arranged between said second shaft and said roll to rotate the roll, manually operable means to connect said first-named shaft and power unit to oscillate said eccentric means and move the roll against the shoe and normally establish a driving relation between said second shaft and said roll, and

5 10 15 20 25 30 35 40 45 50 55

connected thereto, a second shaft projecting from said casing, means including a flexible driving connection operatively arranged between said second shaft and said roll to rotate the roll, manually operable means to connect said first-named shaft and power unit to oscillate said eccentric means and move the roll against the shoe and normally establish a driving relation between said second shaft and said roll, and a second manually operable means extending within the roll to engage the means for rotating the roll to interrupt said normal driving relation and effect a pressing operation.

14. In an ironing machine, a gear casing at one end thereof, a roll and a cooperating shoe, a shaft projecting from said gear casing into said roll, a power unit, eccentric means carried by said shaft within said roll and operatively connected thereto, a second shaft projecting from said casing, means including a flexible driving connection operatively arranged between said second shaft and said roll to rotate the roll, manually operable means to connect said first-named shaft and power unit to oscillate said eccentric means and move the roll against the shoe and normally establish a driving relation between said second shaft and said roll, and a second manually operable means extending within the roll to engage the means for rotating the roll to interrupt said normal driving relation and effect a pressing operation, said last-named manually operable means including an oscillatable shaft having an arm arranged within the roll to engage the means to drive the roll and a handle portion outside of the roll conveniently accessible to the ironing machine operator.

15. In an ironing machine a stand, a gear casing at one end thereof, a roll and a cooperating shoe, a shaft projecting laterally from said gear casing into the interior of the roll, an eccentric carried by said shaft within the roll and arranged upon oscillation of said shaft to move the roll toward and away from said shoe, a second shaft projecting from said gear casing into said roll, a power unit operatively connected to both of said shafts and arranged to continuously rotate said second-named shaft irrespective of the movement of the roll with respect to said shoe, a driven member carried by the roll adapted to be brought into engagement with said second shaft as the roll is advanced toward said shoe and manually operative means extending into said roll to prevent the engagement between said driven member and said second shaft to effect a pressing operation between the roll and shoe.

JOHN W. RACKLYEFT.
